UNITED STATES PATENT OFFICE.

ANIELLO DE VIVO, OF BAYONNE, NEW JERSEY.

SHARPENING DEVICE FOR RAZORS.

977,172.

Specification of Letters Patent. Patented Nov. 29, 1910.

Application filed July 25, 1910. Serial No. 573,744.

To all whom it may concern:

Be it known that I, ANIELLO DE VIVO, a subject of the King of Italy, residing in Bayonne, in the county of Hudson and State 5 of New Jersey, have invented certain new and useful Improvements in Sharpening Devices for Razors, of which the following is a specification.

This invention has for its object to produce a very simple and compact form of a 10 razor grinding device to be operated by a spring motor and automatically grind the blade of a razor uniformly and evenly throughout its length; at the same time to 15 work automatically by merely clamping the blade in the support and winding the spring.

A further object is to provide means for adjusting the stroke of reciprocation of the blade, and also to provide means for controlling the speed of the grinding wheel or 20 quickly arresting its motion.

In the accompanying drawing representing an embodiment of my invention, Figure 1 shows the device in side elevation. Fig. 2 25 is an end view. Fig. 3 is a plan. Fig. 4 is a view of the clamp, and Fig. 5 shows a razor blade that is to be ground.

As indicated in Fig. 5, the razor blade 6 is shown as having its slightly concave side 30 faces *a* and *b* that by repeated honing at the edge portion have additional curve faces *c* and *d*. This will give at the portion of the blade where such grinding has taken place, a form of edge that is entirely too thick, and 35 will not properly flex as is required in the proper use of a razor.

The object of this invention is to produce a concave side surface that is a continuous curve from the edge to the heel of the blade, 40 as indicated inside of the sectional portion of this figure.

The device is shown as comprising a frame denoted generally by 7 in which is mounted a spring motor 8 pivoted between side members 9 and 10. The handle 11 is shown for winding up the motor, that is engaged by the usual pawl and ratchet 12 and 13. At the other end of the frame is mounted a small grinding wheel 14 on a shaft 15, pivotally supported in a bearing portion 16 of a frame. It will be seen that the grinding wheel has its axis at right angles to that of the spring motor shaft 17. Suitable gearing 45 is mounted between the spring motor and the grinding wheel to transmit the motion at a much increased speed for the

grinding wheel. The shaft 16 of the grinding wheel is shown provided with a bevel gear 18 meshing with a gear 19 on a shaft 20 parallel with the shaft of the spring motor. 60 The shaft 20 carries a pinion 21 meshing with a gear 22 on a shaft 23; and the latter shaft carries a pinion 24 meshing with a gear 25 fast on the shaft 17 of the spring motor. By this means it will be seen that 65 the grinding wheel will make a large number of revolutions to one of the spring motor. To control the speed of the grinding wheel, and arrest it when desired, a suitable controlling device is provided, shown in the 70 form of a friction brake. This is illustrated as comprising a brake lever 26 pivoted at 75 27 on the frame, and engaging a brake wheel 28 on the shaft 15 of the grinding wheel. An upright 29 of the frame has a threaded bore in which turns a screw 30 whose lower end is connected to the brake arm 26, by which means the brake arm can be pressed against the brake wheel with a force that can be very finely adjusted. 80

A carriage 31 is mounted to reciprocate on the bottom member of the frame by means of dovetailed guides 32, which carriage slides parallel with the axis of the grinding wheel. The carriage is automatically reciprocated 85 from one of the gearing members, and an arm 33 is shown secured on the shaft 23 and has a slot 34. A connecting rod 35 is pivoted to the carriage at 36 and by means of a bolt 37 is adjustably pivoted in the slotted 90 crank arm 33. By this means the stroke or path of reciprocation of the carriage is varied as desired. The carriage will have an evenly timed reciprocation from the gearing member. The carriage supports a clamp 95 for the razor blade shown separate in Fig. 4 as comprising a channel shaped portion 40 having the sides converging to engage the heel of the razor blade that is slid therein and clamped by screws 41. One of the channel portions is extended at 42 to engage practically the entire face of the razor blade that is not engaged by the grinding wheel as shown in Figs. 1 and 2. This clamp is preferably adjustably mounted on the carriage 100 105 and a carriage 43 is shown having its dovetailed channeled lower face slidable on a dove-tailed top portion 44 of the carriage, and secured in adjusted positions by screw 45. On this carrier is a bracket 46 containing apertures, and the holder has an apertured bracket 47 connecting with the hinge 110

bracket and a clamp screw 48 passes through these two members, whereby the blade holder is mounted to swing on an axis on the holder, parallel with the axis of the grinding wheel, 5 and readily located in adjusted positions. By this means the razor blade is practically universally adjustable relative to the grinding wheel and any desired curvature can be given to the blade by these two adjustments.

- 10 A small cup or receptacle 50 is shown below the grinding wheel and a roller 51 is pivoted therein to project above the level of water or other liquid in the cup, and to engage the bottom of the grinding wheel. By 15 this means the grinding wheel can be supplied with water or oil if desired and kept moistened to prevent undue heating of the blade.

It will be seen that this device is very 20 compact and can be easily transported or put in the pocket and carried around. To grind a razor it is only necessary to wind up the spring with the handle, adjust the blade in the holder and then start the device 25 by releasing the friction brake. The grinding wheel will be rotated and the blade will be evenly and uniformly reciprocated across the face of the grinding wheel whereby a fine cut will be had on its edge. The speed 30 can be readily controlled by the brake and stopped when desired. The device is entirely automatic and once started will continue to operate until the spring runs down, one winding being found practically sufficient for one blade.

It is sometimes desired to replace the 35 grinding wheel 14 by a polishing wheel that should run in the opposite direction in order to cause reversal. The bevel gear 19 meshing with the bevel pinion 18 is mounted 40 on a sleeve 51 sliding on the shaft 20 and secured thereon in adjusted positions by screw 53. This sleeve also carries a bevel gear 52 that when the sleeve is shifted will 45 be brought into mesh with the bevel wheel 18, at the same time the bevel wheel 19 will disengage. Obviously the rotation of the shaft 20 in the same direction will cause a 50 reverse movement to be given to the shaft 15 by shifting these two bevel gears into and out of engagement, and they can be locked by the screw in the desired position.

It will also be observed that the screws 41 55 in the holder 40 can be adjusted to shift the razor blade in the holder toward and from the grinding wheel.

It will be further seen that screws 55 and 56 in the side plate 42 of the holder serve to adjust the blade to advance it toward and 60 from the grinding wheel as desired.

Having thus described my invention, I claim:

1. In a grinder for razors, the combination of a frame, a motor on the frame, a 65 grinding wheel rotatable on the frame, driv-

ing means between the motor and the grinding wheel, a carriage, means for reciprocating the carriage from the motor, a guideway on the frame on which the carriage is movable in a plane parallel with the axis 70 of the grinding wheel, a clamp member arranged to engage a razor blade and to support it on the side opposite to the face being ground, said clamp being adjustably carried on the said carriage, the clamp being 75 adjustable on the carriage toward and from the axis of the grinding wheel, and also adjustable to swing on an axis parallel with the axis of the grinding wheel.

2. In a grinder for razors, the combination of a frame, a motor on the frame, a grinding wheel rotatable on the frame, driving means between the motor and the grinding wheel, a carriage, means for reciprocating the carriage from the motor, a guideway on the frame on which the carriage is movable in a plane parallel with the axis 80 of the grinding wheel, adjustable clamping means for a razor blade on the carriage, comprising a frame having a U-shaped 85 clamping portion to engage the back of the blade and an extension to engage one side of the blade, and screws in the U-shaped portion to engage the blade and position it in the holder.

3. In a grinder for razors, the combination of a frame, a motor on the frame, a grinding wheel rotatable on the frame, driving means between the motor and the grinding wheel, a carriage, means for reciprocating the carriage from the motor, a guideway on the frame on which the carriage is movable in a plane parallel with the axis of the grinding wheel, comprising a frame having a U-shaped clamping portion to engage 90 95 the back of the blade and an extension to engage one side of the blade, and screws in the U-shaped portion to engage the blade and position it in the holder, means for shifting the holder on the carriage toward and from the grinding wheel, and means for swinging the holder on an axis parallel to the axis of the grinding wheel and for clamping it in adjusted positions.

4. In a device of the character described, 100 the combination of a grinding wheel, means for rotating the grinding wheel, a carriage, and means for reciprocating the carriage, of a blade holder comprising a channel shaped portion to engage the back of the 105 blade and having an extension to engage and cover one side face of a blade, an adjusting screw in said extension, and adjusting screws in the channel portions to shift the blade in the holder.

5. In a grinder for razors, the combination of a frame, a motor on the frame, a grinding wheel rotatable on the frame, driving means between the motor and the grinding wheel, a carriage, means for reciprocating the carriage from the motor, a guideway on the frame on which the carriage is movable in a plane parallel with the axis of the grinding wheel, and means for reciprocating the carriage from the motor.

cating the carriage from the motor, a guide-way on the frame on which the carriage is movable in a plane parallel with the axis of the grinding wheel, a clamp member arranged to engage a razor blade and to support it on the side opposite to the face being ground, said clamp being adjustably carried on the said carriage, a carrier slideable on the carriage in a path at right angles 10 to the path of movement of the carriage, a

razor clamp adapted to clamp a razor blade and support the face of the blade opposite to the one being ground on the wheel, said clamp being pivotally supported on the carrier to swing on an axis parallel with the 15 axis of the grinding wheel.
